[57] CLAIM

The ornamental design for an infant carrier, substantially as shown and described.

DESCRIPTION

FIG. 1 is a rear elevational view of an infant carrier showing our new design;

FIG. 2 is a front elevational view thereof;

FIG. 3 is a reduced scale rear perspective view thereof;
FIG. 4 is a left side elevational view of FIG. 1 with a portion of the shoulder strap broken away and omitted for convenience of illustration;

FIG. 5 is a right side elevational view thereof.

FIG. 6 is a top plan view thereof.

The partial showing of shading indicating a fabric texture is understood to be continuous throughout on the surfaces where shown.
